PLEATED TEXTILE FABRIC

Leonard Frischer, New York, N. Y.

Application March 31, 1953, Serial No. 24,277

Term of patent 14 years

(Cl. D92—1)

FIG. 1.

FIG. 2.

Fig. 1 is a plan view of the pleated textile fabric of my design as seen against a dark background and showing the folded edges of the angularly disposed pleats;

Fig. 2 is a similar view of the pleated textile fabric of Fig. 1 as seen against a light background and showing the configuration or width of the pleats.

The opposite face of the fabric presents substantially the same appearance as the face disclosed.

I claim:

The ornamental design for a pleated textile fabric, as shown and described.
